FIG. 8

Charles E. Hutchings, INVENTOR,
Ray L. Stinchfield
BY *Donald H. Stewart*,
ATTORNEYS.

UNITED STATES PATENT OFFICE.

CHARLES E. HUTCHINGS, OF ROCHESTER, NEW YORK, ASSIGNOR TO EASTMAN KODAK COMPANY, OF ROCHESTER, NEW YORK, A CORPORATION OF NEW YORK.

PHOTOGRAPHIC-PLATE HOLDER.

1,380,209.

Specification of Letters Patent. Patented May 31, 1921.

Application filed September 11, 1919. Serial No. 323,184.

To all whom it may concern:

Be it known that I, CHARLES E. HUTCHINGS, citizen of the United States of America, residing at Rochester, in the county of Monroe and State of New York, have invented certain new and useful Improvements in Photographic-Plate Holders, of which the following is a full, clear, and exact specification.

10 The present invention relates to photography and more particularly to photographic plate holders and has for its object to provide a simple and compact device which is made of few parts which may be 15 readily assembled by unskilled labor; a further object is to provide a plate holder which is easily loaded and unloaded in the dark; and a still further object is to provide a locking means for holding the photographic plates in position in the holder which will be on the outside of the holder in an accessible position and yet preserving the smooth outside contour of the plate holder. The invention consists of certain improvements 25 and combinations of parts, all as will be hereinafter more fully described, the novel features being pointed out in the claims at the end of the specification.

In the drawings, in which like reference 30 numerals designate like parts:

Figure 1 is a front elevation of a plate holder constructed in accordance with and illustrating one embodiment of my invention.

35 Fig. 2 is a side elevation thereof.

Fig. 3 is a side elevation showing the latches freed from their catches, the bottom being open.

Fig. 4 is a fragmentary part of the plate 40 holder showing the bottom open in front elevation.

Fig. 5 is a detail of the bottom of the plate holder side, illustrating the spring latch seat.

45 Fig. 6 is a section on line 6-6, Fig. 5.

Fig. 7 is a section on line 7-7, Fig. 3.

Fig. 8 is a section on line 8-8, Fig. 1.

The plate holder of my present invention is designed to be made of wood, although a 50 metal holder might be made embodying the same ideas. In the present instance the plate holder consists of a frame having sides 1 and 2, a top 3, and bottom 4, dark slides 5 being slid in place by handles 7 so as to

cover the plates 6 in a manner well known to 55 the art. Latches 8 hold the dark slides in place. When I refer to plates in this specification I do not limit myself to glass plates coated with a photographic emulsion, for my holder is also well suited for use as a 60 sheath for holding cut films, so that the term "plate" is herein used to designate a base upon which the light sensitive photographic emulsion is coated.

The bottom 4 is normally pressed by 65 springs 9 away from the frame, there being spring fingers 10, apertured at 11 to form a latch over pins 12 in the sides 1 and 2. The sides are recessed at 13 forming seats for the spring latches 10, and have hollowed 70 out portions 14 at the sides of the recess which take the broadened heads 15 of the latches 10, so that an operator may conveniently grasp the ends 15 to draw out the latches until the apertures 11 are beyond the 75 end of pins 12, thereby unlocking the bottom or door 4 so that it will spring out to the position shown in Figs. 3 and 4. When in this open position the plates 6 may be easily removed or loaded by removing or drawing 80 out the dark slides 5.

In order to limit the outward movement of the bottom 4, pins 16 on latches 10 travel in slots 17 in the sides 1 and 2. The latches 10 are fastened to the bottom 4 by screws 85 18 and the pins 16 are preferably provided with long narrow heads 19 arranged transversely of the latches 10. This makes a quick and easily assembled construction. As shown in Fig. 5 the latches 10 are placed so 90 the heads 19 pass through slots 17 in plates 20 fastened by screws 21 to the sides 1 and 2. By rotating latches 10 until the bent portions 22 rest on and can be fastened to the bottom 4 the heads 19 of pins 16 are secured 95 against displacement in slots 17. In this way the spring fingers perform the double function of latches and connections between the sides 1 and 2 and the bottom 4.

To form tracks to guide the bottom 4 100 sliding between open and closed positions I provide small metal plates or flanges 23 fastened to the sides 1 and 2 with pins 24. Slots 25 in the end piece 4 slide about these flanges, and since there are two tracks on 105 each side, the bottom is guided by four slots 25 engaging four flanges 23, so that the movement is smooth and easy. In addition

to forming guides these plates 23 render the joints between the sides 1 and 2 and the bottom 4 light tight so that the sensitized plates cannot be fogged and spoiled. 5 There is also a third function which these tracks 23 perform, that of lifting the downward movement of dark slides 5 in slots 26. This is not so necessary in the type of slide illustrated in the drawings for the 10 handle 7 may limit the downward movement, but it is useful in slides which do not have handles, such as are well known in the art.

The springs 9 are seated in apertures 27 in the bottom 4, and press against a cross bar 28 fastened into the sides 1 and 2. The 15 bottom 4 also has sides 29 slotted at 25 for engaging tracks 23 and across the tops 30 to form slots into which the dark slides 5 fit forming light tight joints. These sides 20 29 slide on opposite sides of cross bar 28, as best shown in Fig. 8.

The plates 6 are held in place at the top by grooves 31 in the top of the plate holder (shown in dotted lines Fig. 1) such as is 25 well known in plate holders of this type, and at the bottom by the sides 29 which, when in closed position, form flanges for holding the plates against outward movement (Fig. 8).

30 The operation of loading is as follows:

Assuming the slides are removed and the bottom 4 released into open position, the frame is held with one hand, a plate is laid in one side and the dark slide inserted and 35 slid in until all but an inch of the plate is covered. A plate is placed in the other side in the same manner, then holding the dark slides 5 so as to push inwardly slightly upon the plates, the bottom 4 is pushed up until 40 the latches catch on pins 12, then the dark slides 5 are moved in to their limit and the retaining pins 8 turned to hold the handles 7 in place. While this is the preferred method of loading, the steps may be altered 45 to suit the individual operator. The holder will load more smoothly when the plates are slightly pressed toward the center, for the edges of the sides 29 can more easily slide past the ends of the plates when held as described, and too the dark slides may be slid 50 directly into grooves 30 of the sides 29 of bottom 4 when the bottom is in closed position.

A plate holder built in accordance with 55 my invention is very simple to operate and build and is adapted for use by the professional or amateur photographer.

What I claim as my invention and desire to secure by Letters Patent is:

60 1. In a plate holder the combination with a frame for holding photographically sensitive material, dark slides insertible into the frame to protect the sensitive material from light, of a spring actuated door attached to the frame, the door being mov-

able into an open and a closed position, and latches for holding the door against the spring pressure.

2. In a plate holder the combination with a frame for holding photographic plates, 70 dark slides for protecting the plates of a slideable door in the end of the frame movable into an open and closed position for placing and removing the plates in the frame, latches for holding the door closed, 75 the latches also forming the connection between the door and the frame in all positions.

3. In a plate holder the combination with a frame for holding photographic plates, 80 dark slides normally covering the plates, of a slideable bottom door, latches to hold the door to the frame, the latches limiting the sliding movement of the door.

4. In a plate holder the combination with 85 a frame adapted to hold plates, the frame being slotted and having an opening at one end, said opening adapted to be closed by a slideable door, of latches for holding the door to the frame, the latches being provided with pins, said latches limiting the sliding movement of the door relative to the frame by means of the pins coöperating with the slots.

5. In a plate holder the combination of a frame adapted to hold plates, the frame being slotted and having an opening at one end, said opening adapted to be closed by a slideable door with latches for holding the door to the frame, each of said latches having a headed pin adapted to be inserted 100 through the slot in the frame, the head of the pin being adapted for insertion in the slot only when the latch is in a position out of alignment with its normal direction of travel in the slot.

6. In a photographic plate holder, a frame, dark slides, a door attached to the frame, the opposite frame edges having seats for spring latches, and latches adapted to fill the seats when the door is closed and to ride up over the edges of the seats when the door is opened.

7. In a plate holder the combination of a frame for holding photographically sensitive material, a slideable bottom to the frame, 115 one of said parts having a groove, and a track arranged on the other of the before mentioned parts adapted to coöperate with said groove, the track comprising a metal plate which forms a light tight joint between the two relatively movable parts.

8. In a plate holder the combination with a frame for holding plates or other light sensitive material, a dark slide insertible into the frame to prevent light from reaching the plate, of a movable bottom door, the sides of the frame each carrying a plate upon which the bottom slides, the plate forming a stop to limit the movement of the dark slide.

9. In a plate holder the combination with a frame for holding plates or other light sensitive material, a dark slide insertible into the frame to prevent light from reaching the plate, of a movable bottom door, a stop for the dark slide comprising a plate which also forms a light baffle to prevent light from leaking between the frame and the bottom door.
10. In a plate holder the combination with a frame for holding plates, of a dark slide insertible into the frame to prevent light from reaching the plates, metal plates carried by the frame, a movable bottom door 15 for the frame, the door adapted to slide on and be guided by the metal plates, the metal plates forming stops for the dark slide and the metal plates providing a light seal so that light cannot enter between the adjacent 20 parts of the frame and the door.
11. In a plate holder for photographic
- plates, the combination of a frame with a door, the door movable to an open or closed position with respect to the frame, springs for moving the door in one direction, the door being substantially U-shaped in cross section, the springs being seated in between the sides of the U-shaped door.
12. In a plate holder for photographic plates, the combination with a frame having 30 openings, of dark slides to cover said openings in the frame, metal plates carried by the frame, a bottom door to the frame substantially U-shaped in cross section, the sides of the bottom door being grooved 35 to receive the ends of the dark slides, and the ends slotted to receive the metal plates.

Signed at Rochester, New York, this 5th day of September, 1919.

CHARLES E. HUTCHINGS.
